(57) **CLAIM**

The ornamental design for a security camera, as shown and described.

DESCRIPTION

FIG. 1 is the front view of a security camera embodying the new design.

FIG. 2 is the rear view of the security camera.

FIG. 3 is the left side view of the security camera.

FIG. 4 is the right side of the security camera.

FIG. 5 is the top plan view of the security camera.

FIG. 6 is the bottom view of the security camera; and,

FIG. 7 is the perspective view of the security camera.

The broken lines depict portions of the security camera in which the design is embodied that form no part of the claimed design.
